NILS J. A. WAHLBERG, OF PITTSBURGH, PENNSYLVANIA, ASSIGNOR TO WESTINGHOUSE ELECTRIC & MANUFACTURING COMPANY, A CORPORATION OF PENNSYLVANIA.

SECTION SWITCH.

1,410,974.

Specification of Letters Patent. Patented Mar. 28, 1922.

Application filed January 5, 1918. Serial No. 210,521.

To all whom it may concern:

Be it known that I, NILS J. A. WAHLBERG, a citizen of the United States, and a resident of Pittsburgh, in the county of Allegheny and State of Pennsylvania, have invented a new and useful Improvement in Section Switches, of which the following is a specification.

My invention relates to section switches and particularly to such switches as are adapted for use in mines or similar places of restricted or irregular over-head character.

One object of my invention is to provide a switch of the above indicated character that shall be simple and durable in construction, and that may be readily mounted on a mine roof, regardless of certain irregularities therein.

Another object of my invention is to provide a switch that permits the operating portion thereof to be readily changed from one side of the main body portion of the same to the other.

A further object of my invention is to provide means for so distributing the stresses imposed on the insulating body portions of such switches as to minimize the amount of wear and the likelihood of fracture thereof.

In the prior art, section switches have been used that have been attached to mine roofs by centrally disposed lugs and that, to install, required turning of the entire switch structure. Very often, overhead conditions are such as to make this an exceedingly difficult or impossible operation. Also, when it was desired to mount such a switch by a lug at each end thereof, difficulty was often encountered in drilling the mine roof for the reception of co-operating suspension studs at the exact positions desired.

Further, it was frequently necessary to carry a stock of switches operable from opposite sides to meet certain service requirements, and the wear caused to the insulating body portions of some section switches by stresses imparted through certain bolts therein, was an objectionable feature.

In practicing my invention, I provide a switch that, by the use of simple interchangeable parts, may be readily adapted to various requirements, such as center or end sus-

pension; may be operated from one side or the other; may be mounted at substantially any desired location in a simple and expeditious manner, and may more evenly distribute certain stresses therein.

Figure 1 of the accompanying drawings is a side view of a section switch embodying my invention; Fig. 2 is a bottom plan view of the switch shown in Fig. 1, and Fig. 3 is a side view of a modified form of section switch embodying my invention.

Sets of bolts 3 and 4 secure longitudinally aligned terminal members 1 and 2 having an air gap 6 therebetween, to the lower edge or face of a main body member 5 of insulating material, such as wood.

Screws 8 secure conductors 7, comprising ends of two sections of an electric line that it may be desired to separate, to the terminal members 1 and 2 which also extend upwardly along the ends of the member 5. The bolts 3 and 4, and screws 10 that extend into the terminal members 1 and 2, rigidly secure conducting straps 9 of copper, or other metal, along the top of the member 5, thus lending mechanical rigidity to the structure and insuring a good electrical path from the conductors 7 to a knife-blade switch 11.

The switch 11 comprises a laterally-extending pivot terminal 12, a blade member 13, a laterally-extending jaw terminal 14, and a handle 15. The bolts 4 rigidly secure the inner end of each of the terminals 12 and 13 between the member 5 and the straps 9. By removing the bolts 4, the switch 11 may be readily placed so as to extend from either side of the member 5, and a switch for disconnecting a section of trolley, or other electric line, is thereby provided that avoids the necessity of having different switches for operation on one side or the other, according to the service or installation requirements.

It is often difficult or impossible to mount a switch having a centrally disposed rigid lug that is adapted to screw upon a depending stud from the mine roof, by reason of the relatively great length of the switch and the difficulty of turning the entire structure in cramped or otherwise restricted positions.

Accordingly, I provide means for centrally suspending my section switch, comprising a

nut or lug 16 having an annular lower flange 17 and an upwardly extending threaded recessed portion 18 for engagement with a stud depending from the mine roof (not shown).

A lug or member 19, disposed at the center of the upper edge or face of the member 5, has downwardly extending portions 20 that embrace the member 5, by engaging the side faces thereof, and are attached thereto by a bolt 21 which extends through a hole 28 in the member 5. An annular upper portion 22 of the member 19 embraces the flange 17 of the lug 16 which is thus held securely in position with respect to the switch structure, but which may be rotated with respect thereto in securing it to its co-operating stud.

When it is desirable to support the member 5 at each end thereof, as shown in Fig. 20, lugs 23, each having a screw-threaded annular recessed upper portion 24 and a flat lower portion 25, may be provided. Horizontal slots 26 in the portions 25, permit longitudinal adjustment of the latter with respect to transverse bolts 27 that extend through holes 29 in the member 5 and the slots 26 to secure the lugs 23 rigidly to the member 5. This longitudinal adjustment is very desirable by reason of the fact that it is not always possible to position the co-operating mine roof studs a given distance apart because of the nature of the roof.

The holes 28 and 29, through which the bolts 21 and 27 of the lugs 19 and 23, respectively, extend, may be all provided during the construction of the device, in which case, the latter may be adapted for ready mounting in either manner above described, or the desired holes may be drilled to permit the 40 one or the other method of mounting. It is seen, however, that a switch is provided which permits, in a very simple and expeditious manner and without the aid of complicated or expensive extra parts, considerable latitude in the matter of positioning the same.

Heretofore, stresses imparted to the insulating body member, similar to the member 5, of such a switch, by trolley conductors, terminals, and bolts that extend therethrough, resulted in undue wear thereto and fracture thereof by reason of the concentration of such stresses between the bolts of relatively small diameter and the same.

Accordingly, I provide countersunk portions in the members 5, adjacent to each of the lower ends of the bolts 3 and 4, in which a washer 30 is disposed. The flat peripheral edges of the washers 30 thus distribute the before-mentioned stresses over a considerable portion of the member 5 and prevent the deteriorating effect of concentrated stresses thereon. Obviously, the washers 30 may be integral parts of the bolts 3 and 4 and may

be of any other suitable size and arrangement.

While I have shown and described a particular form of my invention, many changes may be made therein without departing from the spirit and scope thereof, as indicated in the appended claims.

I claim as my invention:

1. A section switch comprising a longitudinal insulating body member having transverse openings therein adjacent to the ends thereof, a trolley-conductor terminal member at each end of said body member, said terminal members having upwardly extending end portions and trolley-contact portions extending along the bottom of said body member, conducting members each secured, at one end, to one of said upwardly extending portions and extending along the top of said body member, a switch member at the other end of each of said conducting members, and bolts extending through said transverse openings for joining said conducting members to the said bottom portions of said terminal members and securing said switch members in position. 90

2. A section switch comprising a longitudinal insulating body member having a transverse opening therein adjacent to one end thereof, a trolley-conductor terminal member at said end, said terminal member having an upwardly extending end portion and a trolley-contact portion extending along the bottom of said body member, a conducting member secured to said terminal member and extending along the top of said body member to an intermediate point thereon, a switch member connected to said conducting member, and a bolt extending through said transverse opening and connecting said conducting and said terminal members. 95

3. In a section switch, the combination with an insulating member, of a terminal device of substantially yoke shape having its legs disposed one above the other comprising a conducting member having a trolley-conductor-supporting portion, the bottom leg constituting a trolley-contact member and the upper leg constituting a terminal conductor for the switch, and a member joining said legs and attached to said insulating member. 110

4. In a section switch, the combination with an insulating member, of a terminal device of substantially yoke shape comprising a conducting member having a trolley-conductor-supporting portion, a leg constituting a trolley-contact member and a leg extending along the top of said insulating member, a switch member engaging said top leg, and a member for securing said switch member in position and for attaching said terminal device to said insulating member. 120

5. In a section switch, the combination

with an insulating member, of a terminal device of substantially yoke shape comprising a conducting member having a trolley-conductor-supporting portion, a leg constituting a trolley-contact member and a leg extending along the top of said insulating member, a bolt joining said legs and attached to said insulating member, and a member co-

operating with said bolt and having relatively broad surface engagement with the insulating member for effecting a relatively wide distribution of stresses between said bolt and said insulating member.

In testimony whereof, I have hereunto subscribed my name this 22nd day of Dec., 1917. 15

NILS J. A. WAHLBERG.
